UNITED STATES PATENT OFFICE.

WILLIAM F. DURFEE, OF BRIDGEPORT, CONNECTICUT, AND THOMAS EGLESTON, OF NEW YORK, N. Y.

METALLURGICAL GAS-FURNACE.

SPECIFICATION forming part of Letters Patent No. 295,988, dated April 1, 1884.

Application filed June 27, 1882. Renewed March 6, 1884. (No model.)

To all whom it may concern:

Be it known that we, WILLIAM F. DURFEE and THOMAS EGLESTON, citizens of the United States, residing, respectively, at Bridgeport, 5 in the county of Fairfield and State of Connecticut, and at New York city, in the county of New York and State of New York, have invented a new and useful Improvement in Metallurgical Gas-Furnaces, of which the following is a specification.

Our invention relates to improvements in metallurgical furnaces in which gas is used as a fuel, and is intended to facilitate the introduction and equable distribution of air, steam, 15 or other vapor or gas to and in the heating or melting chamber of the furnace at certain stages of the operation, being conducted there-in when such an introduction and distribution are desirable. We attain this result by 20 means of apparatus illustrated in the accompanying drawings, in which—

Figure 1 is a vertical longitudinal section (on line C D of Fig. 2) of a metallurgical furnace (in which gaseous fuel is used) with our improvement attached. Fig. 2 is a horizontal section of Fig. 1 on line A. B. Fig. 3 is a transverse section of the furnace on line F G of Fig. 2. Fig. 4 is a detached view of one of the cold-air pipes shown at E E' in Figs. 1 and 2. Fig. 5 is a cross-section through the valve at the end of cold-air pipes and shows the valve open.

Similar letters refer to like parts in the several figures.

The manner of operating our invention is as follows, viz: When in the course of the treatment of the metal or other substance in the heating-chamber of the furnace it is desired to rapidly reduce the temperature of the furnace, or to rapidly oxidize, or to produce other chemical changes in the material under treatment, the valves V V' in the end of the cold-air pipes E E' are opened and the chimney-damper of the furnace is raised, so as to 35 draw the cold air into the heating-chamber through said pipes E E', and their attached nozzles n n n, &c., and the air-ducts a a a and a' a' a', located in the brick-work of the furnace between the "ports" or flues through 40 which the hot air and gas enter the heating-chamber; as is shown in Figs. 1, 2, and 3. The cold-air pipes E E' are provided with a 45 large nozzle, N, through which air, steam, or other vapor or gas may be introduced to the

5 pipes, and thence through the channels a a' to the heating-chamber of the furnace; but when the nozzles N are used in this way the valves V V' at the ends of the pipes E E' are closed and the supply of the air, steam, gas, or other vapor is regulated by suitable valves 60 in the pipes, which convey them to the nozzles N N.

The cold-air pipes E E' are provided with "spy-holes" s, situated opposite the nozzles n n, through which the condition of the channels a a' and the interior of the furnace can be easily examined and any obstruction in the channels removed. The spy-holes aforesaid are glazed with mica, which is held in an iron frame pivoted on one side, so that it can be 65 turned aside in order to permit a rod to be 70 inserted through the spy-holes into the channels a a', in order to remove any obstruction therefrom.

We are aware that prior to our invention 75 openings for the introduction of air into the heating-chambers of reverberatory furnaces using solid fuel have been made through the bridge-wall and through the roof and side wall in the vicinity of the heating-chambers 80 of such furnaces, and that these openings have been intended to convey air only for the purpose of promoting the combustion of such combustive vapors as had escaped from the fire-box in an unconsumed state; and therefore we do not claim the use of our invention 85 in connection with such fire-box reverberatory furnaces, or for the purpose for which similar openings have been used in such furnaces; but

90 What we do claim as our invention, and desire to secure by Letters Patent, is—

1. In a metallurgical furnace having gas and air ducts communicating with the heating-chamber, the pipes E E', provided with 95 nozzles N n n, for the purpose of introducing air, steam, or other vapor or gas to said furnace, substantially as described.

2. In a metallurgical furnace, the pipes E E', having valves V V', nozzles N n n, and 100 spy-holes s s, substantially as and for the purpose described.

W. F. DURFEE,
THOS. EGLESTON.
